UNITED STATES PATENT OFFICE.

ADOLPH G. KUPETZ, OF NEW ROCHELLE, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed July 19, 1924. Serial No. 726,927.

This invention relates to improvements in typewriting machines, wherein provision is had for feeding a fan-folded web upon a table in the direction of the platen, so that the platen may engage one end of said web and advance the same through the usual line-spacing mechanism as the web is being typed.

In such types of machines a drawback has existed inasmuch as the weight of the relatively heavy carbon-carrier upon which the web is clamped during its movement in the direction of said platen with the added weight of the web and interleaved carbon sheets causes enough inertia to make the rotatable platen, during the line-feeding action thereof, slip relatively to the web, so as to be ineffective to feed the web uniform line space distances.

One of the objects of the present invention is to overcome this disadvantage, as hereinbefore explained, by simple, efficient and inexpensive mechanism so constructed, designed and arranged upon the table over which the web is fed along towards the platen that the web may be slackened just previous to the action of rotating the platen, during the line-feeding operation. The slack thus introduced in the web may be equal to a line-space distance, and when the platen is suddenly and manually actuated by the line-spacing mechanism or by means of operating automatically during the return of the carriage by motor-operated mechanism, such as is shown in the patent to Hart No. 1,325,469, dated December 16, 1919, the line-spacing of the platen takes up the slack in the web between the carbon-carrier and the platen.

Another object of the present invention is to provide simple mechanism for automatically advancing the carbon-carrier, so that the web clamped thereonto may be fed along over the table intermittently and timed with the actuation of the line-spacing mechanism, so that the carbon-carrier is movable forwardly in the direction of the platen at the same time that the platen is itself rotated by the line-spacing mechanism. The result of this mechanism is to remove all stress from the web in advancing the carbon-carrier toward the platen.

A still further object of the present in-

vention is to assure that the carbon-carrier, which feeds the web along toward the platen by an actuation of the line-spacing mechanism, is advanced in rolling contact upon the table just before the line-space slide is operative to revolve the cylinder or platen, so that the initial movement of the carbon-carrier creates slack between the cylinder and the carrier before the cylinder is line spaced to advance the forms and when the forms are carried around the platen, the slack in the web is taken up and there is no jerk or stress exerted upon the web necessary to overcome the inertia of the web-carbons and carbon-carrier, and no slipping of the cylinder or the platen relatively to the web and carbon-carrier can take place.

Heretofore carbon-carriers have been equipped with web clamps serving to clamp the web onto a carrier to cause it to move along with the latter. During the forward operative traverse of the carrier, the means, which has been provided for manually disengaging the clamp on the carrier from the web, is rendered inactive until during the reverse movement of the carrier to carbon-released position. Such manual clamp-releasing means in conventional use has called for the action of two handle bars, one of which is fixed upon the carriage and the other of which moves relatively thereto and is effective to actuate the web-clamping device.

In such types of invention, however, the clamp actuating and releasing handle bar had to be actuated by a push action, which required special attention on the part of the operator, in a manner which is disclosed clearly in the U. S. patent to Smith, No. 1,364,819, granted January 4, 1921. In said patent it is necessary to pull the clamp-operating finger-piece forwardly, while the fixed finger-piece is held by the thumb. In the present invention, means is provided by which the carbon-carrier may also be retracted without releasing the web, if desired, by engaging the fixed handle instead of the floating handle. Furthermore, in operating the floating handle of the present invention to release the clamp from engagement with the web, a pulling action is exerted upon the floating handle for this purpose instead of a pushing action, so that one hand of the

operator can effectuate the release of the clamp without undue exertion and without irksome labor.

Other features and advantages will hereinafter appear.

In the accompanying drawings,

Figure 1 is a top plan view of the present invention mounted in position upon a typewriting machine.

10 Figure 2 is a fragmental sectional view of a pawl and pawl support.

Figure 3 is a transverse sectional elevation of the web-clamp-releasing means, taken on line 3^A-3^A of Figure 1, looking in 15 the direction of the arrows.

Figure 4 is a side elevation, partly broken away, of the present invention mounted on the typewriting machine.

20 Figures 5, 6 and 7 are respectively fragmental detail views, showing the progressive movement and relationship between the rack and co-operating pawl hereinafter described.

25 Figure 8 is a fragmental side view of a portion of the typewriting machine, showing a modification of the present invention.

Referring to the drawings, which are merely illustrative of the invention, 10 designates the front rail of a typewriting machine, preferably the Underwood standard machine, which carries the calibrated rule 11 and relatively to which moves the carriage 12, the rollers 13 of which are guided upon the rail 10. 14 designates the 30 guide-plate in which a line-space lever 15 is movably operated, this lever being fulcrumed at 16, at which point it is provided with a push arm 17 for pushing the spacer slide 18 in a conventional manner against the tension of a spring 19 located in the 35 housing 20 in which the spacer slide 18 moves.

21 designates the usual line-space regulator determining the number of lines over 40 which the web is to be fed by means of the platen 23, and 22 designates the finger-knob of the platen 23.

During the actuation of the conventional spacer slide 18 for line-spacing purposes the 45 usual pinion 24 is intermittently rotated and meshes with gears 25 to rotate the platen and line-space the web.

The present invention is automatically and intermittently actuated by the line-spacing mechanism, and is connected to the latter by a link 26 secured at one end upon a pin 27^a of the slide 18, upon which pin is also located the spring 19 for restoring the slide 18. One arm of the link 26, designated 50 27, inclines upwardly and rearwardly and is twisted at 29, to change the plane thereof for a continuing arm 28 which is connected by a pin 30 to a lever 31, fulcrumed between its ends to a pin 32 fixed upon a 55 bracket arm 35, connected to the carriage 12

of the machine. The lever 31 has a toe 33 projecting within a recess 34 formed upon a rack-bar 58, hereinafter further described.

The side supports or brackets 37 and 38 are secured on a cross-bar 38^a of the carriage, so as to move with the carriage. A table 39 is composed of side bars or sills 40 between which is connected the rear bar 41 and a front bar 42, the longitudinal bars 40^a connecting the front and rear bars 42 and 41 respectively. The table may be conventional. Rollers 43 are suitably journaled upon the under side of the table in brackets 44 and make rolling contact with a rear rail 45 of the machine, which is secured upon a 75 frame 46 mounted upon the main frame 47 of the machine by connections (not shown).

The carbon-carrier is designated 48, and operatively mounted thereupon, at each end thereof, are rollers 49 which make rolling contact with longitudinal rails 50 upon the table 39. This carbon-carrier 48 consists preferably of a base-plate 51 upon which are secured, adjacent each end, stepped uprights 52, which carry carbon-blades 53, usually arranged in superimposed and staggered relation and to which the carbon-sheets are attached to be interleaved between the folds or plies of a fan-folded work-web 54 well known to those skilled in the art. This web travels from a supply-roll (not shown) over the turning bar 55 mounted in standards 56, between side guides 57 mounted upon the turning bar for guiding the longitudinal edges of the web in proper relative position upon the carbon-carrier.

The longitudinal rack-bar 58 has rack-teeth 59 extending longitudinally thereof practically throughout the entire length of the table. Shouldered screws 60 with heads that form a flange are secured at spaced apart points upon the rack-bar 58 and serve as studs within slots formed upon cam-plates 64 which are secured upon the table by means of screws 65 projecting through spacer sleeves 66 which space the plates 64 in a plane parallel with the table 39, as is clearly shown in Figure 4. The forwardly-projecting edge 67 of each plate 64 110 positions the plate 64 in such a manner that the rack-bar 58 is positioned normally medially thereof. Each slot formed in the cam-plates 64 consists of a longitudinal straight slot or track 61 and oppositely inclined diagonal recesses 62 and 63 opening into said straight slot 61 and serving to cam the studs 60 on the rack-bar 58 which project therethrough, to promote a parallel movement for the rack-bar 58.

A retractile spring 68 is secured at one end fixedly to a pin 69 on each plate 64 and has its terminal secured on a pin 70 fixed upon the rack-bar 58, for normally holding the studs 60 against the inner edge of one of 120 the diagonal recesses 62 or 63 of each plate 125

64, and in this position of the studs 60 it will be seen that the rack-bar 58 is held longitudinally of the table and against movement thereon, and at this time the toe 5 33 of the lever 31 disposes the lever 31 obliquely of the longitudinal axis of the rack-bar 58, the spring 19 in the housing 20 of the line-spacing mechanism assisting to so position this lever 31.

10 The carbon-carrier has secured to the under side of its base-plate 51 a foot 84 of a bracket 71 secured thereto by fasteners 85 and formed with a lip 72 parallel to the foot, to which a stud 73 is fixed by a screw 15 threaded into the lip and having a head 74 overlying the lip 72, said stud serving as a center or fixed pivot upon which is fulcrumed a pawl 75 having a nose 76 at one end and formed with a notch or recess 77 at its opposite end to coat with a fixed pin 78 secured upon the lip 72. A spring 80 is coiled snugly within a groove 81 of a collar 79 formed upon the stud 73, and this spring has one terminal 82 secured in the collar 79 and its other terminal 83 secured to the pawl 75. Normally the spring causes the nose 76 of the pawl 75 to project beyond the lip 72 endwise of the carbon-carrier 48.

10 The rails 50 are secured upon bars 40, the sleeves 66 contacting with the bars 40 being held thereto by the screws 65, already explained. The rollers 49 are journaled in supports 87 which are secured to the base-plate 51 of the carbon-carrier 48.

35 89 designates a bar which at its inner end curves downwardly and is fixedly secured upon a side piece 90 extending upwardly from the carbon-carrier 48 at one side. Pins 91 are secured respectively one upon

40 the side piece 90 of the base-plate 51 of the carbon-carrier 48 and the other upon the base-plate 51, and serve to support the inner ends of springs 92, the opposite ends of which springs are secured upon pins 93

45 fixed upon the side arms 94 and 95, respectively, of a clamping device. These arms 94 and 95 are fixed at the ends of a shaft 96 journaled in the stepped uprights 52 on the carbon-carrier 48 having its intermediate

50 portion offset at 97. The side arm 95 is provided with a cam-recess 98 to coat with a roller 99 journaled upon one arm 100 of a bell-crank lever fulcrumed between its ends

55 upon a pivot 102 fixed upon the side piece 90, the other arm 101 of said lever carrying a screw 103 upon which is pivoted the curved end 104 of a shifting or floating bar 105, the latter floating bar 105 having an elongated slot 106 in which slidably projects a

60 headed stud 107 fixed to the bar 89, the free end of the bar 105 projecting beyond and in advance of the bar 89, both bars 89 and 105 being provided with suitable finger-pieces 108 and 109.

65 A plate formed with a longitudinal

groove 110 that extends transversely across and in front of said carbon-carrier 48 is secured to the latter by screws 112. The side arms 94 and 95 of the clamp device are formed with ears 113 to which is secured a 70 movable clamp 111, which may be employed to depress the web 54 into the groove 110 in the plate for clamping purposes, as shown clearly in Figure 4.

In Figure 4 it will be noticed that 75 the table 39 is supported in horizontal position rearwardly of the platen 23, so that the rails 50 are spaced above the housing 20 in which is mounted the spacer slide 18. The table in this case is raised to the 80 elevated position shown in order to provide clearance for the tabulating mechanism 123. However, in Figure 8, it will be noticed that the table 39 is in a lower plane with respect to the corresponding parts of the machine 85 than it is shown to occupy in Figure 4, because the tabulating mechanism 123 is removed in this instance, thereby permitting the rails 50 of the table 39 to be disposed virtually at the same level with the bottom 90 of the housing 20, the housing 20 being below the table in Figure 4. The link 26 shown in Figure 4 is serviceable to connect the slide 18 and the rack-operating lever 31. In Figure 8, the housing 20 is located 95 above the table 39, thereby necessitating a different construction and shape of this connecting link. This latter link 26 is attached to the spacer slide 18 in the same manner as is shown in Figure 4, and has the horizontal projecting arm 115 which inclines downwardly at 116 so as to be connected to the rack-bar 58. The arm 116 of the link 26 curves around reversely at 117 and is twisted at 118 to provide an ear 119, 100 which is secured to the outer end of the lever 31 by a screw 120, said lever being fulcrumed upon one of two arms 121, secured to the carriage 12. The arms 121 have ears 121^a (one being shown in Figure 110 8), through which screws 122 pass and thread into the ends of the front bar 42 of the table 39. By means of this construction, the link 26 is spaced downwardly to the level of the table 39, operating in all other respects the same as the link 26 shown in 115 Figure 4.

The mode of operation of the present invention is as follows: The fan-folded web or other work-web 54 is advanced from a 120 feed-roll (not shown) or other source of supply therefor, and is turned over the turning bar 55 of the frame of the table, and from this point the web is usually pulled over the table, and under the platen 23 during the line-space action of said platen. But owing to the fact that the web is engaged by the carbon-carrier, it becomes necessary to overcome the inertia of both the web and the carbon-carrier in the act of 130

advancing the web through the medium of said platen 23. This has occasioned quite often the slippage of the platen relatively to the web, especially when the return of the carriage is induced automatically, by means of an electric motor.

The present invention overcomes this in such a manner that it is no longer necessary for the platen to suddenly overcome the inertia of said web, carbon-sheets and carbon-carrier. This is due to the fact that the line-spacing mechanism which turns the platen during the line-spacing operation thereof also times and controls the movement of the web toward the platen, so that in this instance at the moment that the platen rotates to frictionally take up the advancing web, the web has already been slightly advanced automatically, so that there is slack in the web at the moment that the line-spacing mechanism begins to rotate the platen.

As the line-spacing mechanism operates, the spacer slide 18 in the conventional manner is slid along this housing 20 after the line-space lever has been moved in its guide-plate 14. As the spacer slide 18 moves, suitable connections including a line-space ratchet-wheel (not shown) operate the pinion 24, which, in turn, meshes with the gears 25 to rotate the platen. As this spacer slide moves it pushes the link 26 rearwardly, as shown in dotted lines in Figure 1, which, in turn, shifts the lever 31, causing the toe 33 of the latter to move toward the right, thereupon causing one reciprocation of the rack-bar 58 to take place. The lever 31 moves the rack-bar 58 longitudinally of the table in a forward direction toward the platen, and springs 68 and 19, at the completion of the line-spacing operation, serve to retract the link 26 and lever 31, and to retract the rack-bar 58 in a rearward direction and thus work a complete reciprocation.

Immediately as the rack-bar starts upon its forward movement, the studs 60 mounted thereon occupy their normal positions at the inner ends of the diagonal recesses 62 of the slots formed in the cam-plates 64, and the teeth 59 of the rack-bar are out of engagement with the pawl 75. As the rack-bar moves forwardly the studs 60, moving therewith, ride forwardly in both a longitudinal and a transverse direction, owing to the inclination of the recesses 62, so that the rack-teeth 59 move transversely into engagement with the pawl 75 mounted upon the carbon-carrier, and thus exert a forward movement upon the carrier in the direction of the platen. By the time the studs 60 move longitudinally in the longitudinal tracks 61 of the cam-plates 64, during the continued movement of the rack-bar 58, the carbon-carrier has been moved a short distance, while the platen 23 is still inactive,

being so timed to perform this rotative function by said spacing mechanism. As the rack-teeth engage the pawl, the latter cannot swing on its pivot 73 because the pin 78 in the recess 77 acts as a stop to prevent this pivotal movement, which movement takes place only during the return movement of said rack-bar 58.

Inasmuch as the work-web 54 is releasably clamped to the carbon-carrier 48, owing to the engagement of the clamp 111 within the groove 110, and owing to the fact that the carbon-sheets (not shown), which are supported upon the carbon-blades 53, are properly interleaved between the several plies of the fan-folded web 54, it follows that this work-web together with the mentioned carbon-sheets are caused to move in unison with the carbon-carrier 48. Therefore, during the slight initial forward movement of the carbon-carrier longitudinally of the table, as a result of the studs 60 riding out of the diagonal recesses 62 of the cam-plates 64, a slight loop or slack is created in the web 54 immediately in back of the platen 23. At this point and while the studs 60 are traversing the longitudinal or straight tracks 61 of the slots, the platen 23 is rotated by the line-spacing mechanism, which also is responsible for the last-named movement of said studs, and, in rotating, said platen, which is in frictional engagement with the work-web, owing to the usual feed-rollers (not shown), exerts a pull upon the loop portion of the web more or less suddenly, so while the carbon-carrier continues its forward motion synchronously with the rotation of the platen there is slack upon the web during this operation. The studs 60, while the platen is still rotating, are caused to be cammed into the other diagonal recesses 63 of said slots in the cam-plates 64 against the tension of the spring 68 which holds these studs stationary in the last-named recesses, thereby shifting the rack-bar 58 laterally back to its first-named normal position and retracting the rack-teeth 59 from engagement with the pawl 75. This results in the carbon-carrier automatically stopping, at which time the platen also stops having taken up the work-web 54 a distance equal to one line-space. It will be understood that after each continuous line-spacing of the platen, the carbon-carrier is intermittently advanced a corresponding distance, because the line-spacing mechanism repeats its operation for each rotative movement impressed upon the platen, which causes the carbon-carrier to execute as many movements as are impressed upon the platen. It will also be understood that upon the cessation of the movement of the line-spacing mechanism, the spring 19 relaxes, restoring the line-spacing parts to normal position by which action the lever 31 is restored to nor-

mal position, thereby pushing the rack-bar rearwardly, so that the studs 60 depending therefrom are impelled out of the diagonal recesses 63, thereby re-engaging the rack-teeth 59 with the pawl 75 of the carbon-carrier. At this time the nose 76 of the pawl is forced backwardly against the tension of the coiled spring 80 as the studs 60 traverse the straight tracks 61 of the slots and ultimately, 10 as these studs return to normal position after riding into the diagonal recesses 62, the rack-teeth 59 are then retracted from said pawl. During the rearward movement of the rack-bar 58, therefore, the pawl re-engages the teeth of the rack-bar without imparting movement to the carbon-carrier. The carbon-carrier, therefore, remains stationary until the next operation of the line-spacing mechanism already explained.

15 The carbon-carrier is fed along until it reaches the end of its forward movement and is located upon the table adjacent the front bar 42. At this time a printed form on the work-web has been typed sufficiently 20 to be ready for a severing action. Usually the mentioned printed form has its last line typed at a point spaced from the division line between this form and the next printed form about to be typed, so that before the 25 printed form already typed can be detached along the tearing-off knife (not shown), the operator depresses the release handle 114 of the swinging platen-frame and brings the platen to its lower forward position, thereby 30 also positioning the gage-member 124 secured to the swinging platen-frame in horizontal position. Now by releasing the feed-rollers (not shown) engaging the under surface of the platen, the operator, while still holding the printed form, pulls the same along and with it the web and carbon-carrier until the advancing edge of said printed form is properly gaged, after which this 35 printed form is detached.

40 It will be understood, however, that before detaching the printed form, the operator engages the finger-piece 108 of the fixed bar 89 and at the same time engages the finger-piece 109 of the relatively slidable or floating bar 105, the action being such that the two finger-pieces are caused to interengage after sliding the finger-piece 109 toward the fixed finger-piece 108, as shown in dotted lines in Figure 4. By thus shifting the floating 45 bar 105, the bell-crank-lever-arm 100 is turned upon the fixed pivot 102, which causes the roller 99 to be raised as it is slidably guided in the cam slot or recess 98 formed upon the side arm 94 of the clamp-device, which action raises this end of the clamp-device on the shaft 96 which acts as a fulcrum point therefor. The raising of the clamp device takes place against the 50 tension of the retractible springs 92, so that the clamp 111 proper is disengaged from contact with the work-web 54, thereby loosely separating the carbon-sheets from contact with the plies of the work-web 54.

55 While the finger-pieces 108 and 109 have been brought together to the dotted position shown in Figure 4, the carbon-carrier may be shifted rearwardly, the release of the clamp taking place almost instantly. As the carbon-carrier is retracted, the carbon-sheets held upon the blades 53 are moved with the carrier and are stripped from the printed forms. During the rearward movement of the rack-bar 58, the pawl 75 mounted on the carbon-carrier is disengaged from the teeth of the rack-bar, and the arrangement of the floating bar 105 with respect to the fixed bar 89 of the carbon-carrier is such that one hand of the operator or typist can effectively move the carbon-carrier upon the table while at the same time releasing the clamp on the carbon-carrier from engagement with the work-web, and it is not necessary for one hand of the typist to hold the carbon-carrier while another hand is engaging the floating finger-piece with a pull action thereon in order to effect release of the clamp from contact with the work-web, as is found necessary in previous devices.

60 It will be noted that the Underwood line-spacing mechanism provides for a sweeping line-spacing movement of the line-spacing lever to effect a triple line-spacing rotation of the platen; that when the line-spacing devices are conditioned for a single line-spacing operation, the line-spacing lever has the same sweeping stroke and idly swings through an inactive arc before becoming effective to rotate the platen; that during this inactive initial sweep of the line-spacing lever, the rack-bar 58 is conditioned to engage with the pawl 75 of the carbon-carrier 48, and during the initial forward movement of the studs 60 over the flat tracks 61, said carrier is drawn towards the platen to create a slack in the composite web; that while the 65 studs 60 are still upon the tracks 61, the line-spacing mechanism becomes active to rotate the platen; that during the remainder of the travel of the studs 60 along the tracks 61, the carbon-carrier is fed in unison with the surface feed of the platen to maintain the slack in the web; that when the studs 60 begin their descent of the recesses 63, the platen-feed and the carbon-carrier-feed are still uniformly the same, and that there is still a slack in the web; that just in advance of a point where said studs will bottom within the recesses 63, the rack-bar 58 becomes disengaged from the tooth of the pawl 75 and the line-spacing mechanism is still active to rotate the platen; that during the further movement of the studs 60 to bottom within the recesses 63, the line-spacing mechanism is effective to rotate the platen and take up the slack in the webs between the platen and the 70

now stationary carbon-carrier; that when the studs 60 bottom within the recesses 63 and further forward movement of the rack-bar 58 is arrested, the line-spacing connections to the platen are simultaneously arrested at the end of the line-spacing movement; and that during the whole line-spacing movement, no stress has been placed upon the section of webs between the platen and the carbon-carrier, and the only drag attached to the platen-feeding of the web is in drawing the short section of the web towards the platen. While the arrangement and proportions of the parts have been described for a single line-spacing operation of the webs around the platen, the relative length of the tracks 61 between the recesses 62 and 63 may be such that records may be made on the webs that will be uniformly separated by two or more line-space distances.

Variations may be resorted to within the scope of the invention, and portions of the improvements may be used without others.

Having thus described my invention, I claim:

1. In a typewriting machine, the combination of line-spacing mechanism, a carbon-carrier, a table upon which said carbon-carrier is movably mounted, a revolvable platen actuated by said line-spacing mechanism, and means conditioned by said line-spacing mechanism for actuating both the platen and the carbon-carrier, said carbon-carrier being actuated to move prior to the movement of said platen.

2. In a typewriting machine, the combination of a revolvable platen, line-spacing mechanism for actuating the platen, a carbon-carrier, a table over which said carbon-carrier is movable, normally inoperative means for line-feeding said carbon-carrier towards the platen, and means conditioned by said line-spacing mechanism before actuating the platen, to render said carbon-carrier-feeding means operative.

3. In a typewriting machine, the combination of a platen, line-spacing mechanism, a table, a carbon-carrier reciprocable upon said table, means movable upon said table and engageable with said carbon-carrier to feed the latter, and means controlled by said line-spacing mechanism for actuating the first-named means, said platen beginning to rotate during the movement of said carrier.

4. In a typewriting machine, the combination with a rotatable platen, line-spacing mechanism therefor, a carbon-carrier, a track upon which said carbon-carrier is guided, means movable in the direction of said platen and engageable with said carbon-carrier to impart movement thereto, means normally holding the first-named means out of engagement with said carbon-carrier, and means controlled by said line-

spacing mechanism for actuating the first-named means.

5. In a typewriting machine, the combination of a revolvable platen, a table, a fan-folded web feeding over said table and towards said platen, line-spacing mechanism associated with the platen to feed the web, and means operated by said line-spacing mechanism and engageable with said web at a point at the rear of the platen, for feeding the web first toward and then with the platen.

6. In a typewriting machine, the combination of a rotatable platen, line-spacing mechanism associated therewith, a web-carrier, a web engaging said platen to be fed a line-space distance, and reciprocating means conditioned by said line-spacing mechanism and engaging said web-carrier for advancing the same as the platen.

7. In a typewriting machine, the combination of a revolvable platen, line-spacing mechanism actuating said platen, a carbon-carrier, means for guiding said carrier toward and from said platen, manual means for urging said carbon-carrier toward and from said platen, and means actuated by said line-spacing mechanism and engaging said carbon-carrier to prematurely impart movement to said carrier toward said platen.

8. A typewriting machine including a platen-frame and a platen revolvably mounted therein, a line-spacing mechanism, a carbon-carrier, a fan-folded web engageable by said platen to be fed thereby, means for guiding said carbon-carrier, means carried by said carrier for holding carbon-sheets interleaved with the plies of said fan-folded web, and means actuated by said line-spacing mechanism for moving the carbon-carrier and the web toward said platen.

9. In a typewriting machine, the combination of a revolvable platen including a line-spacing mechanism therefor, a member vibrated by said line-spacing mechanism in a line-spacing direction, a carbon-carrier manually movable independently of said member toward and from said platen, and means conditioned by said member to automatically reciprocate said carbon-carrier.

10. In a typewriting machine, the combination of a platen including a line-spacing mechanism therefor, a reciprocable carbon-carrier, a web releasably clamped upon said carrier, interleaved with carbons, and engageable by said platen to be fed thereby, and a clutch-mechanism co operative with the line-spacing mechanism and connectible to the carbon-carrier to intermittently reciprocate said carbon-carrier to feed the web.

11. In a typewriting machine, the combination of a platen including a line-spacing mechanism therefor, a carbon-carrier, a web

connected with said carbon-carrier and with said platen, and means controlled by said line-spacing mechanism and operable prior to the rotation of said platen for moving 5 said carbon-carrier and web towards the platen.

12. In a typewriting machine, the combination of a platen including a line-spacing mechanism therefor, a table positioned rearwardly of said platen, a reciprocable carbon-carrier guided upon said table, a fan-fold web between the carbon-carrier and the platen, and means controlled by said line-spacing mechanism and connectible with 10 the carbon-carrier, whereby the rotation of said platen, in line-spacing, will feed the web without stress between said carrier and platen.
13. In a typewriting machine, the combination of a platen rotatably mounted therein, tracks mounted rearwardly of said platen, a carbon-carrier having rolling engagement upon said tracks, a web releasably held upon said carrier and upon said platen. 15 means for line-feeding said platen rotatively, means for initially line-feeding said carbon-carrier and web in the direction of said platen, to create a slack in the web, and means conditioned by the platen-feeding means to take up the whole slack in the web.

14. In a typewriting machine, the combination of a platen rotatably mounted therein, a carbon-carrier, means for longitudinally guiding said carbon-carrier in a direction toward and from said platen, line-spacing mechanism for rotating said platen, a web releasably clamped to said carbon-carrier and fed to said platen, and means 20 connectible to said carbon-carrier and engaging said line-spacing mechanism for automatically connecting and disconnecting the carbon-carrier from the line-spacing mechanism at each actuation thereof.

15. In a typewriting machine, the combination of a platen rotatably mounted therein, a web engageable at one end by said platen to be fed thereby, means reciprocable toward said platen and carrying the web at another point to advance the web towards the platen, line-spacing mechanism operative to rotate said platen, and connections between said line-spacing mechanism and the web-carrying means whereby 25 the web is automatically advanced prematurely to the platen-feed.

16. In a typewriting machine, the combination of a platen rotatably mounted therein, a web having one end in feeding 30 relation with said platen, a carrier movable independently of said platen and engageable with said web to advance the web toward said platen, line-spacing mechanism to initially actuate the carrier independently of said platen to create a slack in

the web, and means rendered operable by the initial actuation of the line-spacing mechanism, to subsequently feed both the platen and the carrier in unison, and then take up the initial slack in the web. 35

17. In a typewriting machine, the combination of a web, a platen to advance the web in line-spacing, a carbon-carrier feedable toward said platen, line-spacing mechanism, connections between said line-spacing mechanism and said platen for promoting an initial free movement of the line-spacing mechanism before rotating the platen, and means automatically operable during the free movement of the line-spacing mechanism to feed the carrier and create a slack in the web that subsequently is taken up by the line-spacing movement of the platen. 40

18. In a typewriting machine, the combination of a web, a platen to feed said web, mechanism for line-feeding said platen, a carrier engaging said web for feeding the web toward said platen, and a clutch operable by said line-feeding mechanism and 45 automatically connectible to the carrier, to first feed the carrier and web and subsequently silence the carrier during a full actuation of the line-feeding mechanism.

19. In a typewriting machine, the combination of a platen including a line-spacing mechanism therefor, a carbon-carrier guided longitudinally in the direction of said platen, a web to be fed jointly by said carrier and by said platen, a rack movable 50 parallel to the carrier and toward said platen by the line-spacing mechanism, and means conditioned by the movement of the rack, to interlock with the carbon-carrier to effect a web-feeding movement of the 55 carrier for a predetermined extent.

20. In a typewriting machine, the combination of a platen including a line-spacing mechanism therefor, a web to be fed by said platen, a carbon-carrier movable 60 with said web, a toothed rack movable parallel with said carrier toward said platen and actuated by said line-spacing mechanism, and means conditioned by the movement of said rack to co-operate with means 65 on the carbon-carrier to first connect and subsequently disconnect the rack from the carrier during the movement of the rack towards the platen.

21. In a typewriting machine, the combination of a carbon-carrier including a web, a platen for feeding said web, line-spacing mechanism for actuating the platen, and means engageable with said carbon-carrier and actuated by the line-spacing 70 mechanism for advancing said carrier and web simultaneously and differentially to the advancing movement of the platen-fed web.

22. In a typewriting machine, the combination of a platen rotatably mounted 75

therein, a table positioned at the rear of said platen, tracks upon said table, a carbon-carrier engaging said tracks to be guided thereby, a web normally interleaved with the 5 carbons, a handle to restore the carrier and strip the carbons from the web, clamping means to bind the web to the carbon-carrier, and a release handle co-operative with the first handle to release the web from the 10 control of the carbon-carrier to promote the stripping of the carbon-inlays from the stationary web.

23. In a typewriting machine, the combination of a platen rotatably mounted 15 therein, a carbon-carrier mounted for reciprocable movement towards said platen, including a web, means on said carbon-carrier for normally clamping said web thereto, manual means for reciprocating said carbon- 20 carrier, a rack movable longitudinally in the direction of said platen, means on said carbon-carrier and engageable with the rack, means for actuating the rack, and line-spacing mechanism for simultaneously 25 rotating said platen and for operating said rack-actuating means.

24. In a typewriting machine, the combination of a rotatable platen, a line-spacing mechanism therefor, a carbon-carrier including 30 a web guided towards and from said platen, and means conditioned by said line-spacing mechanism and engageable with said carbon-carrier to feed the carbon-carrier towards the platen before a rotation 35 thereof, and to silence said carrier before the line-spacing movement of the platen is completed.

25. In a typewriting machine, the combination of a table supported horizontally 40 thereupon, rails upon said table, a platen, a line-spacing mechanism, a carbon-carrier having rolling contact with said rails, a rack longitudinally guided parallel to said carrier, a pawl carried by said carbon-carrier 45 and engageable with said rack, means for laterally shifting said rack to bring said pawl and rack into co-operative engagement, whereby the carbon-carrier moves with said rack, and means actuated by the 50 line-spacing mechanism and connected to said rack to effect line-spacing movements of both platen and carbon-carrier.

26. In a typewriting machine, the combination of a table mounted rearwardly and 55 horizontally thereof, a carbon-carrier reciprocable upon said table, a rack movable longitudinally of said table, a rotatable platen in advance of said table, line-spacing mechanism including a slide conditioned to 60 delay the rotation of said platen, means controlled by said slide for actuating said rack, and means rendered operable upon the actuation of said rack to pull said carbon-carrier towards said platen in advance of 65 the rotation of the platen.

27. In a typewriting machine, the combination of a table projecting horizontally to the rear thereof, a reciprocable rack guided upon said table, a carbon-carrier reciprocable upon said table and parallel to the rack and having means engageable with said rack for a joint reciprocation, means conditioned by the reciprocation of said rack to automatically engage and disengage 70 said rack from the carbon-carrier at each 75 reciprocation thereof, and means to reciprocate said rack.

28. In a typewriting machine, the combination of a platen having a line-spacing 80 mechanism, a table at the rear of the platen, a carbon-carrier on the table reciprocable towards the platen, a rack on the table actuated by the line-spacing mechanism for a reciprocable movement parallel with said carbon-carrier, and rack-shifting mechanism 85 automatically operable to lift said rack into parallelism to and into interlocking engagement with said carbon-carrier to draw said carrier towards the platen.

29. In a typewriting machine, the combination of a rotatable web-feeding platen, a table extending rearwardly thereof, web-feeding means longitudinally reciprocable upon said table, and line-feeding mechanism 90 for jointly actuating said web-feeding reciprocating means and the rotatable web-feeding platen.

30. In a typewriting machine, the combination of a platen having a line-spacing 100 mechanism therefor, web-feeding means reciprocably mounted at the rear of said platen, and means operable upon the actuation of said line-spacing mechanism for intermittently moving said web-feeding means towards said platen a line-space distance, and continuously platen-feeding the web the same line-space distance.

31. In a typewriting machine including a platen and a line-spacing mechanism, a table, a carbon-carrier reciprocable longitudinally of said table, a longitudinally reciprocable rack on said table connected to the line-spacing mechanism, camming guides in which said rack is reciprocable to lift the rack and maintain parallelism between said rack and carbon-carrier at all times, a pawl on said carrier engageable by said rack when the rack is lifted, and means for automatically disengaging said rack and carbon-carrier at the end of the forward reciprocation of said rack.

32. In a typewriting machine, the combination of a rotatable platen, line-spacing mechanism including a line-spacing slide, a 115 table horizontally projecting rearwardly of said platen, a rack reciprocable upon said table, means connecting said rack and said line-spacing slide, whereby said rack is actuated, web-feeding means reciprocable 120 upon said table, and means controlled by 125

130

- 5 said rack and engageable with said web-feeding means for intermittently actuating and stopping said web-feeding means at each line-spacing movement of the slide.
- 10 5. 33. In a typewriting machine including a platen, the combination of line-spacing mechanism including a reciprocable member, a table projecting horizontally and rearwardly of said platen, a longitudinally reciprocable rack upon said table, a plurality of camming guide-plates for said rack, web-feeding means reciprocable upon said table, a one-way pawl mounted upon said web-feeding means, means connecting said rack with said reciprocable member for simultaneous movement therewith, and studs carried by said rack and co-operative with said guide-plates, said studs becoming automatically effective upon the movement 20 of said rack in one direction to lift said rack into operative feeding engagement with said pawl, and effective in a reverse direction to lift the rack and idly vibrate the pawl.
- 25 34. In a typewriting machine including a platen, the combination of a table, longitudinal rails thereon, a carbon-carrier having rollers engaging said rails, a web clamped onto said carrier to be fed thereby, a plurality of cam guides secured upon said table in longitudinal alignment, a rack having studs successively guided laterally and longitudinally by said cam guides to change the plane of said rack, means for automatically restoring said rack to its normal plane at the termination of its predetermined longitudinal movement, platen-feeding means engageable with the free end of said web for advancing the web for line-spacing, means controlled by the platen-feeding means for actuating said rack, and means engageable with said rack during its lateral movement to connect said carbon-carrier for a simultaneous movement with said rack to feed the web prior to the platen-feeding movement of the web and effect a release of the web-carrier prior to the full platen-feeding movement.
- 30 35. In a typewriting machine, the combination of a rotatable platen, a table, a longitudinally reciprocable bar on said table, guide-plates having slots, pins on said bar guided in the slots of said guide-plates, said slots being so shaped that said pins are guided to shift the bar transversely in one direction, longitudinally in a forward direction and transversely in an opposite direction with respect to its first transverse movement, line-spacing mechanism for intermittently rotating said platen, means actuated by said mechanism for operating said rack to move the latter simultaneously with said platen, and means controlled by said reciprocable bar for releasably advancing a web
- 35 over the table, said platen taking up the fed portion of said web.
- 40 36. In a typewriting machine, the combination of a table, a longitudinally reciprocable bar having pins, guide-plates in which said pins project and by which said bar is longitudinally guided, means on said guide-plates for alternately shifting the plane of said bar transversely in opposite directions preceding and following the longitudinal movement of said bar, said bar being provided with a recess, a bracket on said table, a lever fulcrumed between its ends upon said bracket and having a toe projecting into said recess, intermittently operated means engaging one end of said lever for turning the same, whereby its toe will move said bar in an opposite direction, and a web intermittently reciprocable upon said table by said bar.
- 45 37. In a typewriting machine, the combination with a table, of rails extending longitudinally thereof, a carbon-carrier having rollers engaging said rails, stepped uprights oppositely arranged upon said carrier, carbon-sheet holding blades extending longitudinally of said carrier and having their ends supported upon said stepped uprights, a fan-fold web interleaved with the carbons, an upstanding side piece at one end of said carrier, a longitudinally extending handle fixed upon said side piece and terminating in a hand-hold, a clamping device pivoted at one end to said carrier to clamp the web and carbon to said carrier, a bell-crank lever fulcrumed upon said side piece and having one end connected to said clamping device, and an auxiliary clamp-releasing handle supported upon the first-named handle and having one end connected to vibrate said bell-crank lever to control the clamping device.
- 50 38. In a typewriting machine, the combination of a table, rails thereupon, a web-carrier reciprocable upon said rails, a pair of longitudinally extending handle-bars, one of said handle-bars terminating short of the length of the other handle-bar, and fixedly secured upon said carrier to reciprocate the carrier, means for mounting the other handle-bar upon the fixed handle-bar for an independent longitudinal movement thereof, a web-clamping device mounted upon said carrier, and means controlled by said movable handle-bar for engaging said clamping device and controlling the feed of the web.
- 55 39. In a machine for manifolding upon a work-web, the combination with a carriage, a revolute platen and platen-mechanism, of a line-space lever, a driving train ramifying from said lever and traveling with the carriage, one branch of said train acting directly upon said platen-mechanism to line-space the platen step by step, and a

- second branch of said train extending directly to said web upon said carriage to engage the web at the intake side of the platen and line-feed the same step by step toward the platen. 30
5. 40. In a machine for manifolding upon a work-web, the combination with a revoluble web-feeding platen and platen-mechanism, of a line-space lever, a driving train 10 ramifying from said lever, one branch of said train acting directly upon said platen-mechanism to line-space the platen and thereby feed the web step by step, and a second branch of said train extending directly 15 to said web to engage and line-feed the same step by step, said second branch of said train engaging the web at the intake side of the platen, and releasing the web prior to the return movement of said line-space lever 20 to normal position. 45
41. In a machine for manifolding upon a work-web, the combination with a revoluble web-feeding platen and a web-supplying mechanism at the rear of the platen, of a 25 web-feeding lever, driving trains of web-feeding mechanisms ramifying from said lever, one train thereof operating in rear of the platen to feed the web toward the platen, while another train is operating to feed the 50
- platen and said web, and means for restoring both trains idly to normal web-releasing positions at the return of the web-feeding lever. 55
42. In a machine for manifolding upon a work-web, the combination with a carriage, a revoluble platen and a web-supplying mechanism at the rear of the platen, of a web-feeding lever, and driving trains of web-feeding mechanisms upon said carriage 40 and ramifying from said lever, one train thereof operating in advance of a second train, to feed and create a slack in the web upon the carriage before the second train becomes operative to feed the platen and the web. 45
43. In a machine for manifolding upon a work-web, the combination with a revoluble web-feeding platen and a web-supplying mechanism at the rear of the platen, of a web-feeding lever, and driving trains of web-feeding mechanisms ramifying from 50 said lever, one train thereof operating in rear of the platen to feed the web to the platen and release the web in advance of the second train becoming operative to feed the platen and the web. 55

ADOLPH G. KUPETZ.
